UNITED STATES PATENT OFFICE.

EVERETT E. REWICK, OF LOS ANGELES, CALIFORNIA.

DESIGN FOR A CHAIR.

54,863.

Specification for Design.

Patented Apr. 13, 1920.

Application filed October 25, 1919. Serial No. 333,401. Term of patent 14 years.

To all whom it may concern:

Be it known that I, EVERETT E. REWICK, a citizen of the United States, residing at Los Angeles, in the county of Los Angeles and State of California, have invented a new, original, and ornamental Design for a Chair, of which the following is a specification, reference being had to the accompanying drawing, forming part thereof.

The figure is a perspective view of a chair, showing my new design.

I claim:

The ornamental design for a chair, as shown.

EVERETT E. REWICK.

Witness:

VIRGINIA I. BERNINGER.
